UNITED STATES PATENT OFFICE.

GEORGE P. CONANT, OF GENEVA LAKE, WISCONSIN, ASSIGNOR OF ONE-HALF TO JOHN F. CONANT, OF SAME PLACE.

SPACING-INSTRUMENT FOR DRAWING.

SPECIFICATION forming part of Letters Patent No. 290,210, dated December 18, 1883.

Application filed April 7, 1883. (No model.)

To all whom it may concern:

Be it known that I, GEORGE P. CONANT, a citizen of the United States, residing at Geneva Lake, in the county of Walworth and State 5 of Wisconsin, have invented certain new and useful Improvements in Spacing-Instruments for Drawing, of which the following is a specification, to wit:

My invention relates to an improvement in 10 spacing or lining rules and squares; and it consists in certain peculiarities of construction whereby the device is greatly cheapened, rendered less liable to get out of order, and more certain in its action, substantially as will be 15 hereinafter more fully set forth.

In order to enable others skilled in the art 20 to which my invention appertains to make and use the same, I will now proceed to describe its construction and operation, referring 25 to the accompanying drawings, in which—

Figure 1 is a perspective view of my invention; Fig. 2, a longitudinal section of the same; Fig. 3, a modification adapted to space radial lines, and Fig. 4 a detail view.

25 A represents a rule or square, to the upper side of which is secured an arm, B, which extends out at right angles to the blade A, and is slotted, as seen at b. This arm is fitted with a sliding box, C, fitting around the arm 30 and provided with a piece, C', working in the slot b, and having flanges c c, which overlap the upper surface of the arm and hold the two together. Upon this piece C' is secured a thumb-rest, C'', and in the forward 35 end of the arm B is a finger-socket, b', which are used as will be presently explained.

D is a slide having a slot, d, and arranged just over the slot b in the arm B, and just in rear of the piece C'. This slide is adjustably 40 secured to the rear end of the arm B by means of a screw and thumb-nut, D', as shown.

It will be readily understood that when the slide D is drawn back and secured in any position the box C is free to have a limited 45 movement upon the arm B equal to the distance the piece C' may slide back without abutting against the slide D.

In operation the blade is laid upon the pa-

per in any position desired, and the thumb placed in the rest C'' and one finger in the 50 socket b'. After drawing a line along the edge of the blade A it is held in place by the pressure of the finger, while the thumb draws back the box C as far as the slide D will allow. The pressure is then transferred to the thumb, 55 and the blade is drawn back until it rests against the box, and a second line drawn. This operation is repeated, and every line will be exactly parallel with the first and exactly the same space between them. 60

If desired, the blade A may be swiveled to the arm B and the pivot provided with a small pointer adapted to indicate the angle to which the blade may be turned and set, as seen by Fig. 4, and may be varied and set as desired, 65 and the device will be found very convenient for section-lining, or any other use where accurate spacing is desired. The arrangement described may be applied to the head of a T-square with equal effect. 70

In Fig. 3 is shown a modification adapted to space lines radiating from a common center. In this case the arm B, box C, and slide D are all formed on the arc of a circle whose center is at some point upon the front edge 75 of the blade A, and when used as before described the box and arm will be drawn around in a circle, and the lines drawn by the edge of the blade will be found to radiate from a common center and as accurately spaced as when 80 parallel.

It is obvious that instead of a slotted slide, D, a screw might be used, held in a lug upon the arm B, and having its point acting as a stop for the piece C'. 85

Having thus fully described my invention, what I claim as new, and desire to secure by Letters Patent, is—

1. In a spacing-instrument, a ruling-blade provided with a slotted arm having an adjustable gage and a finger-hold, in combination with a box in which the slotted arm moves, provided with a projection engaging with and moving in said slot, and having a thumb-hold, substantially as and for the purpose set forth. 95

2. In a spacing-instrument, the blade A, arm B, having slot b and socket b' , and the adjustable slotted slide or gage D, adapted to be set at any point desired, in combination 5 with the box C, provided with flanged piece C', working in the slotted arm, and the thumb-socket C², all constructed and arranged to operate substantially as and for the purpose set forth.

In testimony whereof I affix my signature in the presence of two witnesses.

GEORGE P. CONANT.
